UNITED STATES PATENT OFFICE.

GEORGE H. ELLIS, OF ST. PAUL, MINNESOTA.

INSULATING PLASTER-BOARD.

1,317,158.

Specification of Letters Patent. Patented Sept. 30, 1919.

Application filed December 5, 1918. Serial No. 265,355.

To all whom it may concern:

Be it known that I, GEORGE H. ELLIS, a citizen of the United States, residing at St. Paul, in the county of Ramsey and State 5 of Minnesota, have invented certain new and useful Improvements in Insulating Plaster-Board; and I do hereby declare the following to be a full, clear, and exact description of the invention, such as will enable others skilled in the art to which it appertains to make and use the same.

My invention has for its object to provide a low cost and highly efficient heat insulating lath board; and to such ends, generally 15 stated, the invention consists of the novel construction and arrangement of elements hereinafter described and defined in the claims.

A board or sheet material of the above 20 character to be commercially valuable, must not only be of low cost, but should be very efficient as a heat insulation and should be of such construction and character that plaster applied thereto will be positively 25 held and interlocked therewith, and moreover, should be of a cellular material that will stretch and compress under a force less than that which will crack the plaster. My improved heat insulating lath board meets 30 all of these requirements.

This improved insulating lath board may be commercially made at low cost from various different fibers, such, for example, as cereal straws disintegrated or pulped and 35 preferably reduced to approximately what is known as "half stock." However, I have found in practice that this heat insulating lath board may, in point of cheapness of manufacture and efficiency of the produced 40 article, be made from pulped waste paper. Waste paper, as is well known, may be obtained in large quantities at low cost in all parts of most countries and especially of the United States.

45 In commercial practice, the waste paper may be purchased, the sulfite and better grades of paper can be sorted out and reused to make high grade paper, and colored paper may be sorted out and the dye 50 stock reclaimed therefrom. I have found that by this practice the salvage obtained will pay for the cost of paper, so that the main bulk of the paper which would be used in making of the insulating lath board, 55 would cost practically nothing. Moreover, waste paper contains sizing which, to a con-

siderable degree, makes water proof the board made therefrom. This waste paper, as stated, is pulped but need not, and preferably is not entirely disintegrated. It is, 60 however, reduced to a pulp of such character that it may be molded or pressed to the desired form with the dovetailed lock grooves formed therein by means of suitable so-called core bars, as will presently appear. 65

The interlocking of the plaster to the board is best accomplished by providing the latter with parallel dove-tailed grooves formed therein for the purpose of giving the board its integral, coherent and self-sustaining 70 form.

The improved insulating lath board and one of the many possible devices for forming the same is illustrated in the accompanying drawings wherein like characters indicate like parts throughout the several views. Referring to the drawings:

Figure 1 is a face elevation showing a section of the lath board;

Fig. 2 is an edge elevation thereof, some 80 parts being sectioned;

Fig. 3 is a section on the line 3-3 of Fig. 1;

Fig. 4 is a section on the line 4-4 of Fig. 1, but showing also plaster applied to 85 the board;

Fig. 5 is a plan view of a mold in which the insulating board may be conveniently made; and

Fig. 6 is a transverse sectional view of 90 Fig. 5.

The insulating lath board above described is indicated by the numeral 7 and its dove-tailed grooves by the numeral 8. The mold illustrated for making the board comprises 95 a rectangular marginal frame 9 which is open at both top and bottom. For forming the dove-tailed grooves in the board, I provide parallel so-called core bars 10, the upper edges of which are dove-tailed in form 100 and the lower edges of which are flanged and mounted to slide in guide bars 11, which, in turn, are supported at the bottom of the box by cross bars 12. The guide bars 11 are provided with laterally spaced 105 ribs 13, the ends of which abut loosely against the sides of the core bars 10. The upper edges of these ribs 13 are below the dove-tailed portions of the bars 10 and they serve to support a sectional bottom 110 screen 14.

The pulp is poured or placed in the mold

- onto the screen 14 until it covers the dove-tailed upper edges of the core bars 10 to the proper depth and then an upper screen 15 is applied on top of the pulp, and the 5 pulp, by means of a press, or otherwise, is tightly compressed. The upper screen 15, as shown, is provided with a marginal frame 16 which, of course, is removable with the 10 said upper screen. After the sheet has been compressed and the surplus water extracted therefrom, the core bars 10 are withdrawn endwise from the board. The core bars are shown as attached at their outer ends to a common connecting bar 17.
- 15 After the board has been thus formed, the mold can be turned upside down and the board will then be deposited on the screen 15, which acts as a tray for supporting the board while it is being dried.
- 20 After the board has been properly dried, its surface may be impregnated or coated with a water proofing material, such as coal tar indicated by the heavy black lines marked 18 on Fig. 2 only.
- 25 Obviously, a flat surface, even of a fibrous board will not give the required positive interlocking connection between the plaster and the board, and hence, such fibrous board must be provided with dove-tailed grooves 30 or other surfaces that will positively interlock the plaster to the board. The plaster has very little elasticity and is easily cracked, and moreover, the plaster will shrink considerably in drying, and hence, 35 will be cracked by any lath board with which it is positively interlocked unless the lath board be of a material that will stretch and compress under a force less than that required to crack the plaster. Not only does 40 the plaster shrink in drying, but varying degrees in temperature of the plaster will cause such materials as wood to expand and contract under varying degrees of moisture, and such material as metal will expand and 45 contract under varying degrees of temperature. Neither wood nor metal, therefore,

have been successfully used as a lath board, that is, as a board or sheet proper against which plaster may be applied and positively interlocked therewith without breaking of 50 the plaster under the varying conditions noted. Metal has been unsuccessfully used in the form of expanded lath to be applied on sheathing boards.

My improved insulating lath board, in 55 addition to its heat insulating quality and its special adaptation to hold plaster without breaking of the latter, performs the function both of sheathing and of lath and may be used on studding or joist, either 60 inside or outside of a building without sheathing or wooden boards of any kind. Of course, where additional strength is required, such boards may be used in connection with the lath board, but they are not 65 necessary.

In Fig. 4, plaster 19 is shown as applied to the lath board, and this plaster, in the operation of applying the same, is formed with integral lock ribs 20 that fill and fit 70 the lock grooves 8, thereby positively interlocking the plaster to the lath board.

What I claim is:

1. A lath board composed of disintegrated fiber formed into a porous, expandible and compressible heat insulating body, 75 having on one of its surfaces depressions adapted to positively interlock with the plaster.

2. A lath board composed of disintegrated 80 vegetable fiber pulp and formed with depressions to positively interlock with plaster applied thereto, the fiber pulp being adapted to stretch and compress under a force less than that which will crack said plaster. 85

In testimony whereof I affix my signature in presence of two witnesses.

GEORGE H. ELLIS.
